Specification for Design.

Patented July 20, 1920.

Application filed February 4, 1920. Serial No. 356,237. Term of patent 7 years.

To all whom it may concern:

Be it known that I, FLORENCE K. REYNOLDS, a citizen of the United States, and resident of San Francisco, county of San Francisco, and State of California, have invented a new, original, and ornamental Design for a Toy Figure, of which the following is a specification, reference being had to the accompanying drawing, forming part thereof.

The figure is a perspective view of a toy figure, showing my new design.

I claim:

The ornamental design for a toy figure, substantially as shown.

Signed at New York, county and State of New York, this 29 day of January, 1920.

FLORENCE K. REYNOLDS.
